Patented Nov. 30, 1920.

UNITED STATES PATENT OFFICE.

DERMOT JOSEPH MOONEY AND DONALD HENRY EMBY, OF LONDON, ENGLAND.

METAL CONSTRUCTION.

1,360,774.

Specification of Letters Patent. Patented Nov. 30, 1920.

Application filed January 14, 1920. Serial No. 351,382.

To all whom it may concern:

Be it known that we, DERMOT J. MOONEY and DONALD H. EMBY, both subjects of the King of England, and residents of London, England, have invented a new and Improved Metal Construction, of which the following is a full, clear, and exact description.

This invention relates to improvements in metal constructions, and more particularly to an improved construction of spar, longeron, or the like, for use in airship construction, an object of the invention being to provide a spar or like device which is composed of relatively thin sheet plates of an improved shape and secured together in an improved manner to form a spar embodying the maximum of strength with the minimum of weight.

With these and other objects in view the invention consists in certain novel features of construction, and combinations and arrangements of parts, as will be more fully hereinafter described and pointed out in the claims.

25. In the accompanying drawings—

Figure 1 is a fragmentary perspective view illustrating one form of our invention;

Figs. 2, 3, 4, 5, 6, 7 and 8 are similar views illustrating modifications; and

30. Fig. 9 is a fragmentary view illustrating a modified form of corner construction.

With all forms of our invention we employ a pair of oppositely positioned plates 1 and 2 of channel form in cross-section and 35 constituting the web of the spar. Flanges 5 at the ends of the channel are secured to plates 3 and 4 respectively and the flanges 5 and the plates 4 constituting the flanges of the spar.

40. In all forms of our invention it will be noted that the plates 1 and 2 are spaced apart so that the spar is of the box girder type and these plates 1 and 2 may be of various shapes, as will more fully hereinafter appear.

45. Referring particularly to Fig. 1, it will be noted that the extreme edges of the plates 3 and 4 and the extreme edges of the flanges 5 are curved or bent inwardly with the edges 50 of the plates confining the edges of the flanges so that these double thicknesses of metal which constitute the flanges of the

spar, have inwardly bent strengthening lips 6 throughout their edges. The plates 1 and 2 shown in Fig. 1 are curved or bulged outwardly at their intermediate portions, as shown at 7, and between said intermediate portions, and the flanges 5 are corrugated as shown at 8.

In the modification illustrated in Fig. 2, 60 the plates 1 and 2 are bulged or curved inwardly at their intermediate portions, as shown at 9, and the flanges 10 corresponding to the flanges 5 of Fig. 1 and the edges of the plates 1 and 2 are curved so that the 65 flanges of the girder formed by the two thicknesses of metal are curved in the arc of a circle and are not flat as in Fig. 1.

In the modification illustrated in Fig. 3, 70 the plates 1 and 2 are relatively straight with corrugated portions or webs 11 adjacent their upper and lower edges, and the flanges 12 at the edges of the plates 1 and 2 are flat and are secured to the plates 3 and 4.

We would have it understood that we do 75 not limit ourselves to any particular means for securing the several plates together as we may employ rivets, or spot welding as a securing means, or any other securing means may be employed that is adapted for the 80 purpose.

In the modification illustrated in Fig. 4, 85 the plates 1 and 2 are corrugated throughout their width and in other respects this structure is precisely like that shown in Fig. 3.

In Fig. 5 we illustrate a modification in which the plates 1 and 2 are of slightly different shape from that shown in Fig. 4, but the general idea of corrugation is carried 90 out and the construction of flange is employed with the addition of filler pieces 13 interposed between the plates 3 and 4 and the plates 1 and 2 at the flanged portions of the spar or girder. Also in this modification we show bolts 14 connecting the plates 1 and 2 and having spacing sleeves 15 on the bolts between the plates to stiffen the spar and we may employ any number of these 95 bolts as desired.

In the modification illustrated in Fig. 6, 100 the plates 1 and 2 are similar in shape to those shown in Fig. 2 with the exception of the fact that the flanges 16 are straight and

confining strips 17 are positioned over the edges of the flanges 16 and over the edges of the plates 3 and 4 and secured to both in any approved manner.

5 In the modification illustrated in Fig. 7, the confining strips 18 are rounded forming beads 19 at their extreme edges and in other respects the structure is like that shown in Fig. 3.

10 In Fig. 8 we illustrate a modification in which the side plates 1 and 2 are of open-work skeleton form and having laterally projecting flanges 20 at vertical portions of the skeleton plate to form reinforced stand-
15 ards.

20 In Fig. 9 we illustrate a fragment of one corner of the beam structure which shows an incline at 21 instead of the vertical or straight portion of the several figures which indicates that the beam may be thus shaped at the corners, if desired.

25 As above stated, in all forms of our invention, we employ channel side plates to form the web of the spar or girder with the flanges and the channels projecting outwardly and secured to the upper and lower plates so that a box girder construction is formed which is relatively light and yet embodies the maximum of strength and the 30 several plates may be variously strengthened by such curvature, angles or corrugations as may be deemed desirable and as indicated in the several figures of the drawings.

35 Various other slight changes may be made in the general form and arrangement of parts described without departing from the invention, and hence we do not limit ourselves to the precise details set forth, but 40 consider ourselves at liberty to make such changes and alterations as fairly fall with-

in the spirit and scope of the appended claims.

We claim:

1. A metal bar construction of the character described, comprising channel plates spaced apart and forming the web of the bar, plates at the edges of the web covering the outer faces of and secured to the flanges of the first-mentioned plates, and said last-
45 mentioned plates having inwardly bent portions located back of the web portions of the first-mentioned channel plates and spacing said channels apart. 50

2. A metal bar construction of the character described, comprising channel plates spaced apart and forming a web of the bar, plates at the edges of the web covering the outer faces of and secured to the flanges of the first-mentioned plates, and said last-
55 mentioned plates having outwardly curved intermediate portions and inwardly projected portions at the edges of the curved portions, said inwardly projecting portions forming a backing or reinforcement against 60 the inner faces of the channel plates. 65

3. A metal bar construction of the character described, comprising channel plates spaced apart and forming the web of the bar, plates at the edges of the web covering the outer faces of and secured to the flanges of the first-mentioned plates, said last-mentioned plates having outwardly curved intermediate portions and inwardly projected portions at the edges of the curved 70 portions, said inwardly projecting portions forming a backing or reinforcement against 75 the inner faces of the channel plates, and said channel plates having longitudinal corrugations.

DERMOT JOSEPH MOONEY.
DONALD HENRY EMBY.
